SPARK PLUG TESTING DEVICE

Filed June 14, 1927

Inventor

Ernest R. Wike

By *Clarence O'Brien*
Attorney

Patented July 16, 1929.

UNITED STATES PATENT OFFICE.

ERNEST R. WIKE, OF DETROIT, MICHIGAN.

SPARK-PLUG-TESTING DEVICE.

Application filed June 14, 1927. Serial No. 198,777.

This invention relates to new and useful improvements in testing devices for spark plugs on internal combustion engines and aims to provide a highly novel, simple and inexpensive means whereby the operator of the machine can readily determine at a glance, just which particular plug of the engine is inactive with the obvious result, that the necessary repairs may be made to the plug or to the wires leading thereto without necessity of testing each individual plug which usually requires the removal of the same from the engine.

Further, the invention consists of a highly ornamental structure that may be readily attached to the instrument board of the motor vehicle.

In the drawings:—

Figure 1 is a front elevation of my improved spark plug testing device.

Fig. 2 is a detail longitudinal section taken substantially on the line 2—2 of Fig. 1, and

Fig. 3 is a detail transverse section taken substantially from the line 3—3 of the same figure.

Now having particular reference to the drawings, my novel testing device consists of an oval-shaped plate 5 of porcelain, fiber, or other non-conducting material, the space thereof being formed intermediate its ends with a longitudinally extending channel 6. At opposite sides of this channel 6, said plate is formed with spaced circular sockets 7, within each of which is arranged a bushing 8, the lower end thereof being provided with a transverse opening 9 for registry with an opening 10 in the block that extends from the outer side thereof to the channel 6 as clearly indicated at Fig. 3.

Adapted for arrangement through the registering openings in each bushing and said plate 5, is a relatively elongated current conducting pin 11 adjustably secured within the plate and bushing by a set screw 12 threaded within a threaded socket in the bushing, above the opening 9 therein. By reason of this conducting means for the current conducting pin it will thus be seen that by reason of this particular connecting means for each conducting pin, the pins at opposite sides of the channel 6 may be moved towards or away from each other, to regulate the space between complementary pins, at opposite sides of said channel.

The conducting pins 11 at one side of the

channel 6 of the plate 5 are unitarily grounded to the frame of the car as indicated in Fig. 1, the conducting pins at opposite sides of said channel being adapted to be selectively electrically connected with the respective spark plugs of the automobile engine, as suggested in Fig. 1.

At this point it may be well to state that at all times the respective conducting pins 11, of each spark plug are spaced apart a distance greater than the points of their spark plugs, with the obvious result that when the plugs are operating properly, the current will jump the point of the plug whereas should the plugs cease to operate on account of becoming fouled, the circuit will be jumped through their respective points 9 of the testing device indicating that that particular spark plug is not firing.

In actual practice, it is preferable that the plate 5 of the tester be arranged within a similar shaped opening in the instrument board of the vehicle as suggested by the dotted line in Fig. 2, said plate 5 at its face being flanged as at 13 for engagement over the edge of the opening in the instrument board. Furthermore a glass panel 14 is set within the face of the plate 5 and maintained therein by a retaining frame 15 which frame and flange 13 are formed with suitable openings to permit the entire unit to be rigidly secured within the opening of the instrument board.

Having thus described my invention, what I claim as new is:—

In a spark plug tester of the character described, a panel of insulating material having a channel in its front face, and a plurality of spaced sockets at its back face and at opposite sides of the channel, bushings arranged within said sockets and having openings at their lower ends communicating with openings in the panel, conductor pins arranged through the openings in the panel and said bushings, and a set screw threaded longitudinally within each bushing and adapted to bite the conductor pin for adjustably securing the pins within the bushings so that respective pins at opposite sides of the channel may be spaced apart a predetermined degree and means whereby one set of bushings may be connected to the spark plug and the opposite set connected to a common ground.

In testimony whereof I affix my signature.

ERNEST R. WIKE.
